UNITED STATES PATENT OFFICE.

JAMES H. BAKER, GEORGE F. SHEVLIN, AND FREDERICK H. BAKER, OF SARATOGA SPRINGS, NEW YORK, ASSIGNEES TO BAKER AND SHEVLIN COMPANY, OF SARATOGA SPRINGS, NEW YORK, A CORPORATION OF NEW YORK.

CENTRIFUGAL PULP-SCREEN.

SPECIFICATION forming part of Letters Patent No. 727,878, dated May 12, 1903.

Application filed October 23, 1902. Serial No. 128,443. (No model.)

To all whom it may concern:

Be it known that we, JAMES H. BAKER, GEORGE F. SHEVLIN, and FREDERICK H. BAKER, citizens of the United States, residing at Saratoga Springs, in the county of Saratoga and State of New York, have invented an Improvement in Centrifugal Pulp-Screens, of which the following is a specification.

Our invention relates to improvements in centrifugal mechanism, and the same comprises improvements upon the devices shown and described in Letters Patent granted to us November 19, 1901, No. 686,962, and February 11, 1902, No. 693,215. Heretofore in these centrifugal devices some difficulties have arisen in the full and complete separation of the good stock from the slivers and in the operation of the air employed in connection therewith, and difficulties have also arisen in connection with the efficient delivery of the stock from the mixing device to the centrifugal wheels of the apparatus, all of which it is the object of our present invention to overcome.

Our invention relates especially to devices for releasing a certain amount of air between the casing and the screen-plates, usually in addition to the devices shown and described in the latter of our patents hereinbefore referred to, and also to devices for closing up a clean-out opening in the upper central part of the structure, and which devices form a distributor for the stock entering the machine.

In our improvement we employ one or a series of hollow columns connected to and forming part of the casing of the centrifugal machine connecting the trough with the top of the screen and a hollow cover-closure for a clean-out opening reaching into the inlet-pipe, which cover-closure extends in and completes the circle of union of the horizontal inlet and vertical discharge pipes to the centrifugal wheels, and at the same time said structure receives a portion of the incoming pulp-stock and deflects the same to the central portion of the inlet and discharge pipes

immediately over the center of the centrifugal wheels, thereby aiding in distributing the incoming pulp-stock, so that it is acted upon by the centrifugal wheels or beaters so with uniformity.

In the drawings, Figure 1 represents a vertical section and partial elevation of our improved centrifugal screen. Fig. 2 is a partial sectional plan of the same at x x of Fig. 1. Fig. 3 is a sectional plan at the line y y of Fig. 1. Fig. 4 is a partial vertical section at the line z z of Fig. 2, and Fig. 5 is a detached elevation showing parts illustrated in Figs. 2 and 4.

a is the vertical revoluble shaft of the machine, provided with suitable bearings and passing through the machine. The centrifugal devices or beater-wheels are provided with hubs 2 3 , which surround and are secured to the said shaft. The uppermost centrifugal device or beater-wheel comprises a cover-plate b , blades 4 , which radiate in curved form from the hub 2 , and an intermediate ring 7 , having perforations 6 . The lower centrifugal device or beater-wheel is provided with a cover-plate c , which forms a bottom for the upper centrifugal device or beater-wheel, and the same is provided with blades 5 . The cover d to the pulp-screen device is made with an opening of substantially the same diameter as the opening in the cover-plate b of the upper centrifugal device, and a cylinder l extends down into the upper beater-wheel through the openings in the cover, rises above the cover, and is provided with a flange secured to the cover and with an inlet-pipe 12 , the paper-pulp being delivered into the center of the machine through the inlet-pipe 12 , the cylinder l , and extensions of said parts to the place where the pulp-stock and water are mixed in regulable quantities, as set forth in the first of our aforesaid patents.

e represents the segmental casing of the machine, and f ring-frames secured thereto and bolted to the cover d and to annular con-

centric cast-metal troughs *g* and *h*. The annular frame *i* fits over the division-walls between the troughs *g* and *h*, and the circular segmental screen-plates *k* are at their lower edges secured to the annular frame *i* and at their upper edges to the ring-frame *l*, bolted to the cover.

A screen-cleaner *m* is employed, as described in our aforesaid patent, and the same is provided with vertical rods *18*, connected to and operated by a curved plate *17*. As in our Patent No. 693,215, we prefer in the present machine to make curved openings in the cover *d* with flanged edges *9* and to provide curved open-work metal plates or gratings *10*, that fit over the openings and within the flanged edges, so that in the operation of the machine the air within the machine under force can escape through these gratings after passing through the screen-plates *k*, said gratings being over the space or chamber formed within the machine between the case *e* and the segmental screen-plates *k*. The parts hereinbefore described while employed in machines heretofore made use of by us form no necessary part of our present invention, but are described for the purpose of a complete structure.

The device in the nature of a hollow column forming part of the casing and connecting the trough with the top of the screen for releasing a certain amount of air between the casing and the screen-plates comprises the following parts: The casing *e* is formed of segments, and at the junction of said segments we prefer to place hollow columns *n* of rectangular form in cross-section. It will be noticed from the structure of the ring-frames *ff* that parts thereof are secured by rivets to the upper and lower edges of the casing-plates *e*. The upper portion is connected with the top *d* of the centrifugal pulp-screen and the lower portion with the trough *g*. At the respective sides of these hollow columns *n* the vertical parts of said frames *f* are respectively connected to said columns and said plates *e* also by rivets. The parts form a complete closure about the circular segmental screen-plates *k* and a casing for the centrifugal pulp-screen.

It will be noticed from Fig. 2 that the inner surface of the hollow column *n* is flush and substantially continuous with the inner surface of the casing *e*, and by reference to Fig. 4 it will be noticed that this column is provided on the outer surface at the lower end with an inclined base *n'* with an inlet-aperture *13* and at the upper end with an exit-aperture *14*, and in this figure arrows show the direction taken by the air confined in the space between the screen-plates *k* and the casing *e*, the same passing through the aperture *13* up the hollow column and out at the exit-aperture *14*.

From Fig. 5 it will be noticed that there are partitions *20* in the central portion of the

hollow column *n* at the upper aperture *14* and outside of the inclined base *n'*. These partitions stiffen the column at said places, and they may extend the entire height of the column or be located simply as shown. This feature we prefer to employ in addition or, in other words, as supplemental to the grating structure *10* in the cover *d* of the pulp-screen. The construction in vertical section of said hollow column *n*, with its inclined base *n'*, prevents the possibility of the good stock after passing through the screen-plates *k* lodging in or clogging up the opening or space in said column, a liberal discharge of air being, however, thus provided for, so that all of the air which passes through the screen-plates *k* by virtue of the action of the centrifugal beater-wheels may escape. Were this otherwise, the most perfect action of the screen-plates *k* in separating the good stock from the slivers would be liable to be impeded and interfered with, as there would be a perceptible back pressure resulting from the air confined in the space between the screen-plates and the casing.

In the cylinder *l*, surmounting the cover *d*, and through which the incoming pulp-stock enters to the centrifugal pulp-screen, we provide a clean-out opening *15* at the side opposite to that at which the stock enters. This opening is closed by a hollow cover-closure *o*, having an edge flange extending all around the same, and when the part *o* is in position, as shown in Figs. 1 and 3, the said flange fits over the edge of the clean-out opening of the cylinder *l*, and said cover-closure in external dimensions agrees with the internal dimensions of the clean-out opening. Upon opposite sides of the cylinder *l* we provide stud-bolts *16*, pivoted to lugs of the said cylinder, said stud-bolts being adapted to swing and having hand-wheel nuts, and on opposite sides of the cover-closure and as continuations of the edge flange thereof we provide lugs *19*, adapted to receive the stud-bolts *16*, by the tightening of which the cover-closure is held securely in place in and to the cylinder *l*. The inner surface of this cover-closure *o* is curved in cross-section and inclined downward in vertical section, (see Figs. 1 and 3,) and a deflector-plate *o'*, formed integral with or connected to the cover-closure *o*, constitutes an extension of said cover-closure, the upper edge thereof coinciding with the lower curved edge of the cover-closure and the free edge thereof being made concentric with the shaft.

The inner portion of the cover structure, that is curved in cross-section and downwardly inclined in vertical section, is provided with a curve the radius of which is about eleven inches, while the radius of the deflector-plate *o'* is much less and only about seven inches. Consequently the deflector-plate is contracted in relation to the inclined surface of the part *o*, and the curved portion of the deflector-plate is substantially concen-

tric to the shaft. Consequently the pulp-stock as it is delivered to the machine is directed toward the shaft at the center of the machine, and a promiscuous delivery and spreading out of the pulp-stock is prevented, the concentration of the pulp-stock at the center facilitating the even delivery of the same at the center of the beater-wheel, insuring each beater-wheel receiving a proportionate amount of the pulp-stock to be acted upon. This structure occupies a position at the opposite side of the shaft to that of the inlet-pipe 12 for the pulp-stock, and in the operation of the device as said pulp-stock enters the machine it is delivered against said inclined surfaces and is by them directed into the central part of the machine, and when falling said pulp-stock is as nearly equally divided as possible between the blades of the respective beater-wheels, so that equal strain is applied to the blades of said beater-wheels in agitating and delivering the same against the centrifugal screen-plates, and the tendency that heretofore existed of delivering said pulp-stock in unevenly-divided quantities to said beater-wheels is obviated, and the machine is therefore caused to run more regularly, with less vibration, and to do more efficient work and treat a larger quantity of material in a given time.

We claim as our invention—

1. In a centrifugal pulp-screen, the combination with a beater-wheel, segmental screen-plates and a casing surrounding the same, of a device connected to and forming a part of the casing and provided therein for the discharge of air from the lower portion of the chamber between the casing and the screen-plates, substantially as set forth.

2. In a centrifugal pulp-screen, the combination with a beater-wheel, segmental screen-plates and a casing surrounding the same, of one or more hollow structures connected to the casing at the intersection of the plates thereof and forming continuations of said casing, with inlet-openings for air at the lower portion and communicating with the chamber between the casing and the screen-plates and with apertures in the outside for air at the upper portions.

3. In a centrifugal pulp-screen, the combination with a beater-wheel, circular segmental screen-plates and a casing formed of segmental plates surrounding the screen-plates, of a series of hollow columns, means for connecting the hollow columns to the casing plates at their points of intersection so that said hollow columns form continuations of the casing-plates with a smooth unbroken surface in the interior, said hollow columns being provided with apertures at their lower ends opening into the chamber between the casing and the screen-plates and apertures at their upper ends communicating with the interior of the columns whereby the pent-up

air in said chamber of the centrifugal screen may escape up the hollow columns into the atmosphere.

4. In a centrifugal pulp-screen, the combination with a beater-wheel, circular segmental screen-plates and a casing composed of segmental plates, of a series of hollow columns at the intersections of said plates, each column being of substantially rectangular form in cross-section having an aperture 13 at the lower inner portion, an aperture 14 at the outer upper portion, an inclined base 15 and partitions 20 adjacent to the upper or exit aperture 14, and at the lower end.

5. In a centrifugal pulp-screen, the combination with a beater-wheel, segmental screen-plates and a segmental casing, of a cover over the beater-wheel and a cylinder fitting thereon at the central aperture thereof, a cover structure closing a clean-out aperture in said cylinder and at the opposite side thereof to the entrance therein of pulp-stock, said cover structure having a downwardly-inclined inner surface and an extension thereof projecting toward the shaft of the centrifugal pulp-screen, substantially as set forth.

6. In a centrifugal pulp-screen, the combination with a beater-wheel, segmental screen-plates and a segmental casing, of a cover over the beater-wheel and a cylinder fitting thereon at the central aperture thereof, said cylinder having a clean-out opening at one side and an opening in the form of an integral pipe at the other side for the delivery of pulp-stock to the machine, a cover-closure of hollow form 100 fitting the clean-out aperture and having an edge flange extending around the edge of said clean-out opening, means pivotally connected to the cylinder and adapted to engage the hollow cover-closure for holding the same in position, the inner surface of said cover-closure being curved in cross-section and downwardly inclined in vertical section, and a deflector-plate extending below and connected to said cover-closure, and of curved and inclined form with its free edge adjacent to the shaft of the centrifugal pulp-screen for diverting the incoming pulp-stock to the central portion of the beater-wheel, so that the same is evenly distributed, substantially as set forth.

7. In a centrifugal pulp-screen, the combination with a top plate having a central aperture, a cylinder fitting and received upon the same and formed with an integral pipe-section at one side for the entrance of paper-stock from a source of supply and at the opposite side thereof with a clean-out opening, of a hollow cover-closure device having parallel vertical sides, a flanged edge fitting over the edge of the clean-out opening of the cylinder, an inner portion curved in cross-section and downwardly inclined in vertical section and a deflector-plate forming a downwardly-inclined extension to said cover-closure.

sure and extending below the same and toward the shaft of the centrifugal pulp-screen, the edge of said deflector-plate being formed of a curve of less radius than that of the inclined part of the cover-closure, and substantially concentric with the shaft, and adjustable devices for connecting the cover-closure in position.

Signed by us this 10th day of October, 1902.
